CLAIM

The ornamental design for the crosswise electronic game board, as shown and described.

DESCRIPTION

FIG. 1 is a top plan view of the crosswise electronic game board; and

FIG. 2 is a top left perspective view of the crosswise electronic game board shown in FIG. 1;

FIG. 3 is a bottom plan view of the crosswise electronic game board shown in FIG. 1;

FIG. 4 is a front plan view of the crosswise electronic game board shown in FIG. 1;

FIG. 5 is a back plan view of the crosswise electronic game board shown in FIG. 1;

FIG. 6 is a right plan view of the crosswise electronic game board shown in FIG. 1, the left plan view being a mirror image thereof;

FIG. 7 is a right perspective view of the crosswise electronic game board shown in FIG. 1; and,

FIG. 8 is a right perspective view of the crosswise electronic game board shown in FIG. 1.

The broken lines in FIG. 1 through FIG. 8 are for environmental purposes only and form no part of the claimed design.
